UNITED STATES PATENT OFFICE.

JOHN E. FREEBERG, OF SARLES, NORTH DAKOTA.

LIQUID-DISPENSING DEVICE.

Application filed June 10, 1926. Serial No. 115,037.

The invention relates to liquid dispensers of a type for use in connection with barrels and analogous liquid containers, and the principal object of the invention is to provide an exceptionally simple and inexpensive, yet an efficient and reliable device of this nature which may readily be attached to or detached from a barrel or the like and operated while said barrel or other container 10 is resting on a floor, it being unnecessary with this invention to elevate the barrel or reservoir and permit discharge of the liquid by gravity, as a suction pump is provided for creating a partial vacuum in a dispensing container, thus inducing the liquid to flow into such container from the barrel or other reservoir.

With the foregoing in view, the invention resides in the novel subject matter herein-after described and claimed, the description being supplemented by the accompanying drawings.

Figure 1 is a perspective view showing the invention attached to a barrel.

Figure 2 is a top plan view.

Figures 3, 4, and 5 are sectional views as indicated by the correspondingly numbered lines of Fig. 2.

The numeral 6 on the drawings above 30 briefly described, designates a horizontally elongated body of wood or metal, said body in the present disclosure, having a downwardly projecting, flat-bottomed boss 7 at one end to rest upon the head 8 of a barrel 35 9 or analogous reservoir. This body 6 has a port 10 which at one end, opens through the outer end of said body, while the other end of said port is in communication with a liquid discharge tube 11 which is intended 40 to extend through an opening 12 in the head 8 and reach to a point near the bottom of a reservoir 9. A threaded connection 13, embodying a suitable gasket 14, is preferably provided between the body 6 and the tube 45 11, and this tube is preferably though not necessarily formed from glass.

A dispensing container 15 is supported by the outer end of the body 6 for disposition at the exterior of the reservoir 9, and a hollow valve member 16 which passes vertically through the body 6, is provided for placing the interior of said container in communication either with the inner or the outer portion of the port 10. When this valve member 50 is set as in Fig. 3, liquid may flow from the reservoir 9 into the dispensing container 55

15, under the influence of a partial vacuum created in the latter, in a manner hereinafter described. At this time, a discharge valve 17 at the lower end of the container 15 is 60 of course closed. When the valve member 16 is turned to such a position as to place the container 15 in communication with the atmosphere, through the outer end of the port 10, discharge of the liquid from the container 15 is permitted when the valve 17 is 65 opened. In order that any desired quantity of liquid may be drawn into and then discharged from the container 15, the latter is 70 preferably graduated as shown in Fig. 1 and is formed of glass so that the liquid level may be readily viewed when it reaches any desired graduation. A separate cap 18 75 formed of metal, is preferably provided for the container 15 and this cap may be threaded to the container and secured to the lower side of the body 6 in any desired manner. At its lower end, the container is preferably 80 tied to the reservoir 9 by an appropriate bracket 19 having a portion 20 which, by a bolt 21, is clamped around a coupling 22 used for connecting the container with the discharge valve 17. The bracket 19 may be temporarily secured to the reservoir by 85 screws or nails 23.

At one side of the body 6, I dispose a suction pump cylinder 24. The cylinder shown has its opposite ends provided with caps 25 and 26 respectively, the cap 25 being 90 preferably permanent with regard to the cylinder whereas the cap 26 is detachably threaded on said cylinder. The cap 25 is provided with a laterally extending attaching plate 27 which is disposed at a vertical plane and is secured by screws or the like 95 28 against the inner end of the body 6, said plate 27 having a horizontal attaching flange 29 which is adapted to be anchored by screws or other fasteners 30, to the head 8.

The end of the cylinder 24, adjacent the 100 cap 26 may be secured to the body 6, by a strap 31 and fasteners 32, the latter also securing the cap 18 to said body.

By the construction and arrangement above described, simple and inexpensive provision is made not only for mounting the pump cylinder upon the body 6, but for attaching this body to the head of a reservoir.

The inner end of the cylinder 24 is connected by a suction line 34 with the interior 110 of the dispensing container 15, one terminal of this line being preferably connected with

the cap 18. The other end of the suction line is by preference provided with an arched portion 35 which permits a valve casing 36 to be disposed vertically, said casing containing a check 37 which prevents back-flow of air through the line 34. A suitable piston 38 is located in the cylinder 24 and is provided with a piston rod 39 extending through the outer end of said cylinder and provided with a handle 40. The construction of this piston is such that when it is pulled outwardly, air is drawn from the container 15 through the suction line 25 and the check valve and into the pump cylinder, the valve 17 being then closed and the valve 16 in communication with the inner end of the port 10. Upon each inward stroke of the piston however the check 37 closes and the air which has been drawn into the cylinder 24, discharges past the piston. Thus, by reciprocation of this piston, sufficient suction may be created in the dispensing container 15, to cause the travel of liquid from the reservoir 9 through the tube 11, passage 10 and valve 16, into said container. As soon as the liquid level rises to the desired extent in the container 15, the position of the valve 16 is reversed, thus cutting off the in-flow of liquid and opening the upper end of the container 15 to the atmosphere, so that air may enter said container and permit the discharge of the liquid when the valve 17 is open.

As excellent results may be obtained from the general construction shown and described, it is preferably followed. However, within the scope of the invention as claimed, variations may be made.

I claim:

1. A liquid dispensing means comprising a horizontally elongated body having a downwardly projecting boss at one end adapted to rest upon the head of a reservoir, means for detachably securing said body to the reservoir, a liquid conducting tube connected with said body and projecting downwardly

therefrom for reception in the reservoir, said body having a longitudinal port which communicates with said tube, a dispensing container secured to and projecting from the outer end of said body, said container having a discharge valve at its lower end, valve means for placing said container in communication with said port and tube or in communication only with the atmosphere, a suction pump cylinder extending longitudinally of and mounted on said body, a valve suction line from said cylinder to the interior of the dispensing container, a suction creating piston in said cylinder, and an operating rod for said piston extending to the front end thereof and having a handle.

2. A liquid dispensing means comprising a horizontally elongated body whose inner end is adapted to rest upon the head of a reservoir, a liquid conducting tube connected with and projecting downwardly from said inner end of the body for reception in the reservoir, said body having a longitudinal port communicating with said tube, a dispensing container secured to and projecting from the outer end of said body, said container having a discharge valve, valve means for placing said container in communication with said tube and port or for placing it in communication only with the atmosphere, a suction pump cylinder disposed longitudinally at one side of said body, and an attaching plate projecting laterally from said cylinder and disposed in a vertical plane, said plate being secured against the inner end surface of said body and being provided at its lower edge with a horizontal flange intended to be temporarily secured to the head of the reservoir, a suction line from said pump cylinder to said dispensing container, a suction creating piston in said cylinder, and an operating rod for said piston extending to the interior of the cylinder and having a handle.

In testimony whereof I have hereunto affixed my signature.

JOHN E. FREEBERG.
